Primary Examiner — Patricia A Palasik*(74) Attorney, Agent, or Firm* — Harness, Dickey & Pierce, P.L.C.(57) **CLAIM**

The ornamental design for a lube assembly housing, as shown and described.

DESCRIPTION

FIG. 1 is a front-top perspective view of a lube assembly housing;

FIG. 2 is a rear-bottom perspective view thereof;

FIG. 3 is a front plan view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The phantom lines are for illustrating portions of the lube assembly housing, and do not form part of the claimed design.
